(57) **CLAIM**

The ornamental design for an optoelectronic sensor, as shown and described.

DESCRIPTION

FIG. 1 is a perspective view of an optoelectronic sensor showing our new design;
FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof;
FIG. 8 is a perspective view of an alternative embodiment of the optoelectronic sensor;
FIG. 9 is a front view of the optoelectronic sensor of FIG. 8;
FIG. 10 is a rear view of the optoelectronic sensor of FIG. 8;
FIG. 11 is a right side view of the optoelectronic sensor of FIG. 8;
FIG. 12 is a left side view of the optoelectronic sensor of FIG. 8;
FIG. 13 is a top view of the optoelectronic sensor of FIG. 8; and,
FIG. 14 is a bottom view of the optoelectronic sensor of FIG. 8.
